RELEASABLE SUPPORTS FOR ROOFS IN
UNDERGROUND MINESNorman James Muschamp and Frank Cowlishaw,
Mansfield, England

Application July 3, 1951, Serial No. 234,966

Claims priority, application Great Britain April 13, 1951

3 Claims. (Cl. 248—354)

This invention is for improvements in or relating to releasable supports for roofs in underground mines, and is particularly concerned with supports of the type incorporating relatively movable parts with inclined surfaces by which the effective height of the supports may be changed from an inoperative non-supporting height to an operative supporting height. Examples of this type of support are described in the specification of our co-pending patent application Serial No. 205,046, now abandoned, which discloses a support having one or more posts, each post having an upper inclined face associated with it and a tapered member permanently fastened to it and being capable of displacement on said inclined face to change the effective height of the post; in this construction the displacement is effected from a chain or the like by which the support is towed, and stops are employed for limiting movements of the tapered members such that the effective maximum and minimum heights which each post may assume is predetermined. Generally, with this type of support, separate top beams of wood are provided, and because the roof is usually uneven, packing pieces often have to be employed.

An object of the invention is to avoid the necessity for said separate wood beams and packing pieces by providing a self contained support. It is desired that, during the progressive cutting of coal from the working face, the newly formed roof should be supported as soon as practicable, and a further object of the invention therefore is to provide an improved roof support which is self contained and is particularly suitable for use in confined spaces.

The invention provides a roof support for coal mines and the like comprising a body structure, a top beam permanently connected to the structure and disposed substantially horizontally at the upper end thereof, and relatively movable parts by which the top beam may be raised and lowered. Preferably the top beam is movable up and down initially through a predetermined distance and subsequently through a variable distance, conveniently by relatively movable parts having co-operating inclined faces. Preferably the structure is comparatively narrow consisting of two posts connected by a bridge and having the top beam extending along the bridge, and relatively movable parts having co-operating inclined faces are provided at or near each end of the top beam, and the beam is connected to the structure by means which permits raising or lowering of the respective ends to different extents. Conveniently said parts consist of, the body structure, main movable tapered members co-operating with the structure and having a predetermined movement for obtaining the predetermined adjustment (for example in the manner and by the means described in the specification of our patent application Serial No. 205,046) and additional movable tapered members conveniently co-operating with said main movable tapered members and with the top beam, for obtaining the variable adjustment. The top beam is conveniently a channel member and the said additional member extend transversely through the channel members and are provided with stepped surfaces for locating them in different positions of adjustment.

Because in a support according to the invention the top beam is permanently connected and is adjustable for

2

height, the support is self contained and packing pieces are unnecessary. Furthermore a support as above, when having only two posts and therefore being of comparatively narrow nature, is particularly suitable for use in confined spaces. This latter support may be disposed for example parallel to, or at right angles to, the coal face. If desired, in a support according to the invention, the top beam may extend for an appreciable distance beyond the support in cantilever manner so as to support the roof where uprights cannot be satisfactorily fitted.

The above and other features of the invention are disclosed in detailed description given by way of example of the particular embodiments illustrated in the accompanying drawings in which:

15 Figure 1 is a side view of a support according to the invention, and

Figure 2 is an end view of Figure 1 partly in section.

Referring now to the drawings, a roof support is provided particularly for use in coal mines and comprising a 20 pair of spaced uprights (one of which is indicated at 1) said uprights being connected at their upper ends by a bridge 2. This bridge 2 has upper inclined surfaces 3, 4 on which bears tapered wedge or chock members, one of which is shown at 5. Preferably the uprights 1 are H sectioned girders and the bridge 2 is composed of a pair of plate members suitably welded to opposite sides of the uprights 1. Each wedge or chock member 5 conveniently constructed by a pair of side plates 5a, 5b connected by a pin 6 and spaced by a member 26; each of these side plates 5a, 5b has an inclined undersurface, bearing on the appropriate inclined faces 3, 4 of the bridge plate members.

There is also provided a top beam 7 at the upper end of the support and disposed substantially horizontally with each end overlying the respective uprights. This top beam is preferably of channel shape and consists of a corrugated upper number 8 to which there is fastened, by welding, downwardly depending spaced walls 9 and 10. These walls 9 and 10 fit on opposite sides of the bridge 2 and the channel member is conveniently retained

40 connected to the bridge 2 by a pin 11 forming trunnions, and a slot 12 in each wall 9, 10. There is also provided a pair of wedges, one of which is shown at 13 extending transversely of the channel member 7 and bearing at its lower edges on the upper edge of said walls 5a, 5b of the wedge or chock 5; its upper inclined edge co-operates with a correspondingly inclined surface 14 formed by a filling member 15 in the base of the channel member 7. Preferably as shown, each wedge 13 has its lower edge stepped

45 i. e. formed with horizontal spaced surfaces 16 and intermediate inclined surfaces 17 and the wall 5a of each wedge or chock 5 has its upper edge at a lower level than the upper edge of the wall 5b to allow for the taper of the wedge 13; conveniently said upper edges of the

50 walls 5a and 5b are horizontal to register with horizontal surfaces of the wedge and the said wedge 13 preferably has a hole 18 at its apex for a chain or the like.

In use it is desired for the wedge or chock members 5 to be moved from the inner and raised operative position, automatically, as the support is moved away from

60 its roof supporting position and conveniently for this purpose the support is modified in accordance with the specification of our patent application Serial No. 205,046 and to which reference is directed for full details. Briefly, means are provided permanently connecting the wedge

65 or tapered members 5 to the support and said means are displaceable (between stops to limit the movement) through the medium of operating means and a chain or the like; said chain or the like is adapted to pull the support out of the supporting position and substantially simultaneously cause movement of the wedges or chocks 5

70 to their inoperative positions whereat the channel top

beam 8 is lowered. When the support is being erected the wedges are raised by hand and the stepped wedges 13 are hammered in to tighten the top beam 8 up to the roof, one wedge being driven further in than the other if necessary to ensure contact of the top beam with the roof at least at both ends.

Because of the comparatively narrow nature of the support, a number of them may be disposed at desired intervals at right angles to the coal face the top beams 8 may project in cantilever manner towards the coal face if desired; furthermore additional supports according to the invention may be provided located parallel to the coal face for example between said cantilever supports. If and when desired the said chains or the like may be conveniently guided for example by right angle tubular members having flared ends such that the operation of the wedge or chock members 5 is effected by a pulling action on the chain or the like in a direction at right angles to the general plane of the support.

We claim:

1. Roof supporting apparatus for coal mines and the like comprising, in combination, an elongated base plate adapted to serve as a runner; an elongated supporting structure fixed to said base plate, extending along the length thereof and upwardly therefrom and being provided with oppositely inclined top surface portions extending inwardly and upwardly toward each other from opposite ends of said supporting structure, respectively; a pair of chocks respectively located on said oppositely inclined top surface portions of said supporting structure for sliding movement therealong, each of said chocks having opposite side walls engaging said supporting structure and having top substantially horizontal flat surface portions located at different elevations; an elongated channel-shaped beam extending along the length of said supporting structure, being located over the same, and having opposite side walls between which said chocks are located, said side walls being formed with two pairs of opposite elongated cutouts respectively extending upwardly from said chocks and overlapping the same; and a pair of wedge members respectively extending through said pairs of cutouts in a direction transverse to the length of said beam and supporting structure and each having a top surface engaging said beam, said wedge members respectively having bottom surfaces engaging said chocks, and each of said bottom surfaces of said wedge members having a pair of spaced substantially horizontal flat surface portions located at different elevations and respectively engaging said top surface portions of said side walls of each chock, said flat surface portions of each wedge member being interconnected by a bottom surface portion thereof which is inclined to said flat surface portions.

2. Roof supporting apparatus for coal mines and the like comprising, in combination, an elongated base plate adapted to serve as a runner; an elongated supporting structure fixed to said base plate, extending along the length thereof and upwardly therefrom and being provided with oppositely inclined top surface portions extending inwardly and upwardly toward each other from opposite ends of said supporting structure, respectively; a pair of chocks respectively located on said oppositely inclined top surface portions of said supporting structure for sliding movement therealong, each of said chocks having opposite side walls engaging said supporting structure and having top substantially horizontal flat surface portions located at different elevations; an elongated channel-shaped beam extending along the length of said supporting structure, being located over the same, and having opposite side walls between which said chocks are located, said side walls being formed with two pairs of opposite elongated cutouts respectively extending upwardly from said chocks and overlapping the same, said beam having between said side walls a transverse wall portion provided with a bottom sur-

face which is inclined to said top, horizontal surface portions of said chocks; and a pair of wedge members respectively extending through said pairs of cutouts in a direction transverse to the length of said beam and supporting structure and each having a top surface of the same inclination as and engaging said bottom surface of said transverse wall portion of said beam, said wedge members respectively having bottom surfaces engaging said chocks, and each of said bottom surfaces of said wedge members having a pair of spaced substantially horizontal flat surface portions located at different elevations and respectively engaging said top surface portions of said side walls of each chock, said flat surface portions of each wedge member being interconnected by a bottom surface portion thereof which is inclined to said flat surface portions.

3. Roof supporting apparatus for coal mines and the like comprising, in combination, an elongated base plate adapted to serve as a runner; an elongated supporting structure fixed to said base plate, extending along the length thereof and upwardly therefrom and being provided with oppositely inclined top surface portions extending inwardly and upwardly toward each other from opposite ends of said supporting structure, respectively; a pair of chocks respectively located on said oppositely inclined top surface portions of said supporting structure for sliding movement therealong, each of said chocks having opposite side walls engaging said supporting structure and having top substantially horizontal flat surface portions located at different elevations; an elongated channel-shaped beam extending along the length of said supporting structure, being located over the same, and having opposite side walls between which said chocks are located, said side walls being formed with two pairs of opposite elongated cutouts respectively extending upwardly from said chocks and overlapping the same, and said beam being formed in at least one of said side walls thereof with an elongated slot extending downwardly towards said supporting structure and overlapping the same; a pair of wedge members respectively extending through said pairs of cutouts in a direction transverse to the length of said beam and supporting structure and each having a top surface engaging said beam, said wedge members respectively having bottom surfaces engaging said chocks, and each of said bottom surfaces of said wedge members having a pair of spaced substantially horizontal flat surface portions located at different elevations and respectively engaging said top surface portions of said side walls of each chock, said flat surface portions of each wedge member being interconnected by a bottom surface portion thereof which is inclined to said flat surface portions; and a pin fixed to said supporting structure and extending through said slot to interconnect said beam and supporting structure while freeing said beam for movement toward and away from said supporting structure.
